UNITED STATES PATENT OFFICE.

WILLIAM STEWART, OF BROOKLYN, NEW YORK.

BOTTLE-STOPPER.

SPECIFICATION forming part of Letters Patent No. 320,189, dated June 16, 1885.

Application filed January 20, 1885. (No model.)

To all whom it may concern:

Be it known that I, WILLIAM STEWART, of Brooklyn, in the county of Kings and State of New York, have invented a new and useful 5 Improvement in Bottle-Stoppers, of which the following is a full, clear, and exact description.

Reference is to be had to the accompanying drawings, forming a part of this specification, in which similar letters of reference indicate 10 corresponding parts in all the figures.

Figure 1 is a side elevation of one of my improved bottle-stoppers shown as applied to a bottle. Fig. 2 is a sectional side elevation of the same taken through the line *x x*, Fig. 1. 15 Fig. 3 is a plan view of the same.

My invention relates to improvements in bottle-stoppers; and it consists in the peculiar construction and arrangement of parts, as hereinafter fully described, and pointed out 20 in the claim.

A represents an ordinary bottle, into the mouth of which is fitted a tubular packing or bushing, B, having around its upper end a flange to rest upon the edge of the mouth of 25 the bottle, as shown in Figs. 1 and 2. The inner surface of the inner end of the packing B is flared or beveled to form a seat for the ball C, placed within the bottle A. The ball C can be made of cork, hollow metal that will not 30 corrode, or plated with a non-corrosive metal, or of other material not affected by moisture or acid. The ball C must be of such a buoyancy that it will readily float upon the liquid contained in the bottle. The packing B is 35 held from being forced out of place by outward pressure from the contents of the bottle by an annular cap, D, placed upon the flanged outer end of the packing B and having three (more or less) arms, E, formed upon or attached to its outer edge. The arms E are so 40

formed or bent as to extend along the neck of the bottle, and are secured to the said neck by a wire, F, passed around the said arms and neck, and around which the said arms are bent, as shown in Figs. 1 and 2. 45

The improvement is designed to be used in bottling soda-water and other liquids generating gases, and thus producing an outward pressure.

In using the improvement the ball C is 50 placed in the bottle, and the packing B is inserted in the mouth of the said bottle and secured in place by the cap D E and the wire F. Then as the bottle is filled the ball C rises with the liquid until it comes to its seat in the lower 55 end of the packing B, where it is held in place by the outward pressure of the contents of the bottle. When the bottle is to be emptied, it is held in a horizontal or inclined position and the ball C is pushed from its seat by means of 60 a rod or other suitable implement and at once rises through the liquid to the highest part of the said bottle, and thus allows the contents of the bottle to flow out freely.

Having thus fully described my invention, I 65 claim as new and desire to secure by Letters Patent—

The herein-described bottle-stopper, consisting of the tubular packing B, provided with a flanged outer end and having the inner surface of its inner end beveled and flared, the ball-float C, the fastening-wire, and the metal cap provided with the arms E, adapted to have their ends bent around the said fastening-wire, as set forth. 70

WILLIAM STEWART.
